GIOVANNI EMANUELE ELIA, OF PARIS, FRANCE.

SUBMARINE MINE.

1,057,950.

Specification of Letters Patent. Patented Apr. 1, 1913.

Application filed January 9, 1912. Serial No. 670,176.

To all whom it may concern:

Be it known that I, GIOVANNI EMANUELE ELIA, of Hotel de Crillon, Place de la Concorde, Paris, in the French Republic, have 5 invented certain new and useful Improvements in Submarine Mines, of which the following is a specification.

This invention relates to submarine mines which are automatically exploded when 10 struck by a ship.

According to this invention the spring controlled striker is connected to the anchoring device in such a manner that its movements relatively thereto are controlled by a 15 movable arm which, on the mine being struck, is so moved as to allow the striker to be automatically cocked and then released to cause explosion of the mine.

The invention will be more particularly 20 described with reference to the accompanying drawing in which:—

Figure 1 is an axial section of the percusion mechanism of the mine. Fig. 2 is a partial section on the line 2—2 in Fig. 1. 25 Fig. 3 is a general view of the mine.

A chamber *b* is arranged in the interior of a sphere *a*; this chamber may be in the shape of a cone and to its apex there is fixed 30 a tube *c* in which a cartridge *d* provided with a detonator *e* is arranged. The cartridge *d* is supported by a cylinder *f* screwed into or otherwise rigidly connected to a frame *g* fixed to the hollow sphere *a*.

A piston *h* adapted to reciprocate in the 35 cylinder *f* carries a striker *i* and a spring *j* bearing on a collar *k* in the cylinder *f* controls the striker. The striker rod *m* is provided with a reduced portion *n* ending in a head *o* and this head is imprisoned by the 40 claws *p* pivoted to a common pivot *q* carried by a rod *r* to which a shackle *s* is fixed for securing the anchoring cable.

The heads 2 of the claws *p* are adapted 45 to slide in the lower part of the cylinder *f*, which maintains them in the position illustrated in the drawing, while a spring *t* constantly tends to separate the claws from each other.

The rod *r* ends in a collar *u* which 50 normally bears upon the inner end of an extensible arm *v*, *v'* of ordinary construction, pivoted at *z* to the mine, and the whole of the parts described are kept watertight by means of an extensible joint *w*. A spring 55 key *x* (Fig. 2) is provided for locking the

extensible arm *v*, *v'* in the position represented in the drawing.

When the parts of the mine are assembled the key *x* is arranged in the position shown in Fig. 2 in which it prevents any movement 60 of the arm *v*, *v'* around its pivot and also prevents its extension, the key being locked in position on one hand by a block *y* of sal ammoniac placed behind it, and on the other hand by an axis or pin *y'* also of sal ammoniac passing through its head and engaging into the lugs of its support. The inner end *v'* of the arm *v*, *v'* then prevents the collar *u* from protruding from the mine and maintains all the parts in the position shown 70 in Fig. 1, the spring *j* not being cocked.

When the mine is immersed, the anchoring cable attached to the shackle *s* holds the mine at the desired depth, acting through the collar *u* on the inner end *v'* of the lever *v*, *v'*. When the mine has been immersed for a certain time, the block *y* and the sal ammoniac pin *y'* dissolve (Fig. 2), the key *x* is withdrawn by the action of the spring *x'*, and the arm *v*, *v'* extends under the action of the spring *v*² and is then in such a position that it is free to oscillate on the pivot *z*. 80

If a ship should strike the mine, the mine is caused to rotate about its vertical axis by friction against the ship's hull and in this rotation the extensible arm *v*, *v'* being stopped by the ship's hull, pivots about its axis *z*. Its inner end *v'* then escapes from the collar *u* and the mine tends to rise owing 90 to its buoyancy. Accordingly the sphere *a* and the parts connected therewith ascend while all the parts integral with the rod *r* remain at the same depth. This relative movement cocks the spring *j* while the claws *p* slide in the lower part of the cylinder *f*. When the heads 2 of these claws pass beyond the lower edge of the cylinder, they 95 separate under the influence of the spring *t* and release the head *o* of the striker which, owing to the release of its spring *j*, strikes the detonator *e* and explodes the mine. 100

The advantages are as follows:—This mine is simple in construction and comprises a small number of parts, thereby rendering it certain in its operation and reducing its cost. The provision of a striker which is cocked only by the passage of a ship, that is to say when the mine should become operative, affords increased security in manipu- 110

lating the mine and prevents fatigue of the spring of the striker. The operation is effected by the action of mechanical parts and of the buoyancy of the mine, in such a manner that if the mine is not anchored it presents no danger to navigation. The position described might be reversed, that is to say the extensible arm might be arranged at the upper part of the mine, although the arrangement described is preferable in view of the greater simplicity of the construction. The explosive charge might be arranged at the upper part of the mine instead of occupying the lower part, as in the example illustrated.

The submarine mine embodying the invention may be held stationary by a beam anchored to the sea bottom, or it may be utilized as a floating mine.

Having now particularly described and ascertained the nature of my said invention and in what manner the same is to be performed, I declare that what I claim is—

1. In a submarine mine, a receptacle for receiving an explosive mixture, a tank surrounding and supporting said receptacle so as to cause the same to float, a cap-receiving device, a reciprocating pin adapted to strike said cap and explode the same, means for normally holding said pin against movement including a contact arm, and means for forcing said pin against said cap when said contact arm has been moved in respect to said tank.

2. In an automatically operating submarine mine, a tank for causing the mine to float, an anchor device arranged to hold the mine at any desired depth, a pivotally mounted contact arm arranged to have a free pivotal movement in respect to said tank whereby when a ship strikes said tank and rotates the same, said arm will be held stationary, a reciprocating member normally supported by said arm and released when said arm has been rotated in respect to said tank, a spring brought under tension by the movement of said reciprocating member, a pin actuated by said spring when the same has been released, means for releasing said spring when the same has been brought under a predetermined tension, and means for containing an explosive mixture including a detonating cap.

3. In an automatic submarine mine, a float, a cartridge receptacle mounted in said float designed to contain a cartridge and a cap therefor, a firing pin adapted to strike said cap, a sleeve formed with an abutment, a spring arranged in the sleeve and bearing at one end against said abutment and at the

opposite end against said pin for normally forcing said pin toward said cap, a pair of pivotally mounted pawls engaging the bend of said pin formed with projections engaging said sleeve whereby the pawls are held in engagement with the pin, an anchoring attachment connected with said pawls and with a stationary anchor, and a pivotally mounted locking arm arranged with one end projecting beneath said anchoring attachment whereby the float is connected with the anchoring attachment and said pawls are held in engagement with said pin until said arm has been moved out of engagement with said anchoring attachment whereupon said float will move upwardly and said anchoring attachment will remain substantially stationary, resulting in a longitudinal movement of said pin against said spring, said movement continuing until said pawls have been moved out of said sleeve and consequently disengaged from said pin for permitting the pin to move under the action of said spring against said cap.

4. In an automatic submarine mine, a float, means for connecting the mine with an anchor, means for containing an explosive substance arranged in the float, mechanism arranged adjacent said explosive substance for causing the explosion thereof when actuated, an arm pivotally mounted on said float and normally engaging the means engaging said anchor whereby the float is held from rising and said mechanism is held from operation, a locking pin extending through said arm for locking the same rigidly against rotation whereby said anchor and said float are positively locked together, a spring acting on said locking pin for tending to disconnect the same from said arm, and a block of soluble material arranged in the path of movement of said pin for preventing the spring from disconnecting the locking pin from said arm until the soluble material has been dissolved by the water whereby the device is positively locked during the operation of placing the same and automatically unlocked by the action of the water on the soluble material, said float being adapted to be turned freely upon being struck by a ship independently of said arm resulting in the releasing of said mechanism and a consequent explosion of said explosive substance.

In testimony whereof I have hereunto placed my hand at London, England this fifteenth day of December 1911.

GIOVANNI EMANUELE ELIA.

In the presence of two witnesses:

EUSTACE H. BARKER,

ARTHUR T. WAGHORN.
